UNITED STATES PATENT OFFICE

ARTHUR C. HAYDEN, OF BROCKTON, MASSACHUSETTS

HEEL

Application filed March 24, 1926. Serial No. 97,090.

The invention to be hereinafter described relates to heels for shoes and more particularly to rubber heels. A large percentage of shoes now manufactured are equipped with rubber heels. The retail shoe dealers desire to have their names on the tread faces of the rubber heels, and frequently shoe manufacturers also desire to have their names thereon. It is customary for the shoe manufacturer to purchase the rubber heels for his shoes from a manufacturer who specializes in making rubber heels. It is not practicable for the rubber heel manufacturer to equip himself with the many different dies or molds which would be required for making the heels of shoes with names of the many different dealers thereon.

One of the purposes of the present invention, therefore, is to provide a heel which may have a standard form suitable for all shoe manufacturers and retail dealers, and to this end the heel is formed to provide a shallow recess of substantial area in the 25 tread side of the heel and located well in from the margins of the tread face of the heel. The heel is made in a suitable die or mold formed to produce the recess, and the rubber is vulcanized after the recess is 30 formed so that the heel is in a condition to be applied to a shoe and be structurally ready for wear.

In order that the desired names may appear on the heels ordered, disks or members are provided and formed to fit in the recesses with their outer faces flush with the tread faces of the heels. These disks are made in dies or molds which are made to produce the names on the outer faces of 35 the disks, and the letters of the names may desirably stand out from the faces of the disks in embossed form. Preferably the disks are of rubber and the letters are of the same material. Simple and efficient 40 means is provided for securing the disks in the recesses. The heel manufacturer furnishes the shoe manufacturer a supply of these disks which bear the name of the shoe manufacturer or the names of the different 45 retail dealers who are his customers, or the 50

names of both the shoe manufacturer and the dealer. When an order is received by the shoe manufacturer from a customer, he selects a sufficient number of disks bearing that particular customer's name, and these 55 disks are quickly and easily inserted in the recesses of the rubber heels of the shoes required to fill the order. Similarly, appropriate disks are selected and applied for filling all orders received.

If the name of the retail dealer appeared on the bodies of the heels as an integral part thereof and the operative by mistake applied to shoes rubber heels having the name of the wrong dealer thereon, it would 60 be necessary for him to rip off the entire rubber heels from the shoes and put the proper rubber heels thereon. By the present invention this is not necessary, since in the event of mistaken application of disks 65 to the heels which are applied to shoes, the disks may be removed and the correct disks applied without the necessity of the trouble and inconvenience of tearing off the entire 70 heels from the shoes.

Heretofore, when a shoe dealer found it necessary to discontinue a brand or change the marking of heels, it has frequently happened that he had a large supply of the 75 obsolete heels on hand, and it has been 80 necessary to stand a substantial loss for these heels or else go to the trouble and expense of scouring off the old mark. This procedure is not practicable from a commercial standpoint. By the heels of the 85 present application, if it becomes necessary to change the name or mark on the heels, it is merely necessary to remove the marker disks from the heels and insert others in 90 their places, and this may be done quickly, 95 easily and with very little expense.

The character of the invention may be best understood by reference to the following description of a good form thereof shown in the accompanying drawings, wherein:

Fig. 1 is a section through a heel embodying the invention;

Fig. 2 is a section similar to that shown.

in Fig. 1, showing the rubber marker disk inserted in the heel recess;

Fig. 3 is a view of the bottom of the heel shown in Fig. 1;

5 Figs. 4, 5, 6 and 7 are views of similar rubber disks having different names thereon, any one of them being adapted for application to the heel;

10 Fig. 8 is a section through one of the disks; and

15 Figs. 9 and 10 are respectively detail views of the flanged socket and nail.

Referring to the drawings, the heel shown therein as one good form of the invention, 20 comprises a body 1 of rubber which may have a suitable tread face 3, in the present instance provided with ring-like buttons 5 formed integral with the body of the heel and distributed in the marginal portions 25 of the heel which receive the brunt of the wear. Each of these buttons may have a central hole 7 extending down therethrough and passing through a metal washer 9 embedded in the body of the heel, the holes being adapted to receive the usual nails for securing the rubber heel to the shoe.

25 Formed in the body of the heel is a shallow recess 11 preferably of substantial area, and in the present instance, circular in shape, said recess being located centrally of the heel and surrounded by the marginal portions of the heel which receive the brunt of the wear. A nail hole 13 extends from the center of the bottom of the recess 30 through the body of the heel, and communicates with a small recess 15 at the rear face of the heel. The heel thus formed is vulcanized so that the heel is in condition to be applied to a shoe and be ready structurally for wear.

40 In order that the names may appear on the heels of the shoes ordered, disks or members 17 are provided having the desired names or marks on the outer faces of the members, said disks being formed of rubber in suitable dies or molds. The disks are of a thickness corresponding to the depth of the heel recess 11. Each disk may be provided with a nail 19, in the present 45 instance having a head 21 seated in a flanged socket 23 embedded in the rubber disk. The nail has a hook 25 of substantial length at the end thereof and preferably at an angle with respect to the shank 24 of the nail which is somewhat less than 90°.

50 To apply the marker member to the heel recess 11, it is merely necessary to present its nail to the hole 13 at the bottom of the recess 55 11 and by simple manipulation the nail can be pushed into the hole and cause the hook end to enter the rear recess 15 and so interlock with the bottom of the recess as to prevent the disk from escaping from the recess 60 11. In this operation the body 17 is bent

65 over U-shaped away from the hook 25 whereby the hook can be inserted through the hole 13 and when the body returns to its normal shape the parts assume the position shown in Fig. 2. In the course of this operation the nail head 21 may rock in the socket 23 somewhat, due to the elasticity of the rubber disk, and thereby avoid dislocating the socket 70 therein. The latter will remain in proper position for distributing any pull on the nail head to the rubber disk. The recess 15 has a depth sufficiently greater than the thickness of the hook of the nail to prevent in use any pressure on the hook tending to 75 push the disk 17 out of its receiving recess. 80

85 Any of many differently marked disks of standard form are adapted for insertion in the heel recess which is of standard form to conform to the variety of differently marked disks. As stated, the heel is structurally complete and ready for wear without the marker member which is neither designed nor intended as a wear resisting member. On the contrary, it is purposely constructed and disposed so that its mark will 90 be preserved as long as possible and should be distinguished from wear resisting plugs or inserts. The marker member has important advantages. Among these is the elimination of the necessity of the rubber 95 heel manufacturer having the large expense of providing many different molds for his customers having provision for producing different names on and integral with the heels as a whole. A further advantage is 100 the facility with which the shoe manufacturer may select the retail dealer's marker plugs and apply the same to the heels to fill his orders. And a further advantage resides in the fact that heels having discontinued brands or marks thereon and remaining 105 on hand, do not need to be junked, and thus a great saving is effected.

110 It will be understood that the invention is not limited to the specific embodiment shown, and that various deviations may be made therefrom without departing from the spirit and scope of the appended claims.

What is claimed is:

115 1. A rubber heel for application to a shoe comprising an elastic rubber body having a tread face with a shallow recess of substantial area therein, an elastic rubber member fitting into said recess having an outer face flush with the tread face of the body, a flanged socket embedded in the rubber member, and a nail having a rounded head seated in said socket and a shank projecting out from the member into the body with a hook at the end thereof for securing the member 120 into the recess.

125 2. A rubber heel for application to a shoe comprising an elastic rubber body having a tread face with a shallow recess therein of a depth relatively small as compared to the 130

thickness of said body, said recess being located well in from the rear edge of the body, an elastic rubber member fitting into said recess with its edge in close contact with the wall of the recess, said member having a face with an area much less than the area of the tread face of the body, and means fixed in the member and having a deflected free end adapted to detachably secure the member to the body.

3. A rubber heel for application to a shoe comprising an elastic rubber body having a tread face and a recess located inwardly of the edge periphery of the heel and extending partially into the heel body from said face, the heel having a second recess opposite the first recess and extending partially into the heel body from its upper face and a hole extending through the heel from the bottom of one recess to the bottom of the other recess, a cooperating member fitting into the recess and having tread marking indicia on its outer face, and means permanently carried by the member and including a shank projecting from the rear face thereof and through the hole and provided with a laterally deflected end for engaging against the bottom of the second-named recess to hold the member within its recess.
